CLAIM

The ornamental design for a rotatable ring stand phone case as shown and described.

DESCRIPTION

FIG. 1 is a front, right and top perspective view of a rotatable ring stand phone case, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the rotatable ring stand phone case shown in another configuration of use.

The dashed broken lines depict portions of the rotatable ring stand phone case that form no part of the claimed design.

1 Claim, 9 Drawing Sheets
